UNITED STATES PATENT OFFICE.

APIAUS CLAUDIUS SWAIN, OF MERCED, CALIFORNIA.

GAS-MACHINE.

SPECIFICATION forming part of Letters Patent No. 368,982, dated August 30, 1887.

Application filed August 10, 1886. Serial No. 210,546. (No model.)

To all whom it may concern:

Be it known that I, APIAUS CLAUDIUS SWAIN, a citizen of the United States, residing at Merced, in the county of Merced and State 5 of California, have invented a new and useful Improvement in the Method of and Apparatus for Manufacturing Illuminating-Gas, of which the following is a specification.

My invention relates to an improvement in 10 gas-machines; and the object of my invention is to provide a machine adapted to make an illuminating-gas from a mixture of gasoline vapor and atmospheric air which is capable of being stored in a suitable reservoir or gas- 15 meter and of being forced through gas-pipes to any desired distance without appreciably reducing its pressure or affecting its illuminating qualities.

To this end my invention consists in the 20 peculiar construction and combination of devices that will be more fully set forth herein-after, and particularly pointed out in the claims.

My invention further consists in the method 25 of forcing gasoline under pressure into retorts containing heated air, and mixing the vapor thus formed with atmospheric air in suitable proportions to produce an illuminating-gas.

In the drawings, Figure 1 is an elevation of 30 a gas-machine embodying my improvements. Fig. 2 is a perspective view of the same. Fig. 3 is a vertical transverse sectional view taken on the line *x x* of Fig. 1. Fig. 4 is a vertical longitudinal sectional view taken on the line 35 *y y* of Fig. 2.

A represents a pair of retorts comprising each a vertical cylindrical jacket, B, made of sheet or plate metal, and provided with a top, C, which is bolted on the upper end of the 40 jacket. A packing of asbestos, D, is placed between the upper end of each jacket and the cap. Through the center of each retort extends a vertical pipe, E. These pipes E have their lower ends, which extend nearly to the 45 bottom of the retorts, open, and thereby communicate with the lower sides of the retorts. Surrounding each pipe E, near the upper end thereof, is an encompassing or enveloping pipe, F, which extends upwardly above the 50 top of the retort and downwardly therein for a suitable distance. The lower end of the pipe F communicates with cylindrical baskets

G, which are made of sheet metal and are provided near their upper ends with a series of escape-openings, *g*. The said baskets are maintained in the upper portion of the retort. 55

H represents a horizontal pipe, which connects the upper ends of the pipes E. From the center of the pipe H extends a horizontal branch pipe, I, and on each side of the said 60 branch pipe in the pipe H is located a stop-cock, K.

The upper ends of the pipes F are closed, and the lower ends of the said pipes communicate with the upper portions of the baskets 65 G. From the upper end of the pipes F extend horizontal branch pipes L, which communicate with the upper ends of vertical depending pipes M. The lower ends of the said pipes M are closed, and in the said pipes are located 70 vertical pipes N, the lower ends of which are open and communicate with the lower ends of the pipes M.

O represents a horizontal pipe which connects the upper ends of the pipes N. From 75 the center of the pipe O extends a pipe, P, and on each side of the said pipe P in the pipe O is located a stop-cock, R. On the outer sides of the stop-cocks in the pipe O are located outwardly-opening check-valves S. 80

T represents a pipe which extends from the pipe L of the right-hand retort to the pipe H, communicating with the latter on the left-hand side of the left-hand stop-cock K. In the said pipe P is located a stop-cock or globe-valve, U. 85

The pipe I communicates with a horizontal pipe, V, which is located between the pipes H and O. The said pipe V is provided at one end with a vertical pipe, W, having its lower and upper ends closed. Inside the pipe W is 90 located a vertical pipe, W', the upper and lower ends of which are open, and the upper end of the said pipe projects above the upper end of the pipe W and carries a pressure-indicating gage, W², which may be of any suitable preferred construction. From the pipe V, near the pipe W, extends a branch pipe, X, which communicates with a vertical pipe, Y. The said pipe Y is provided near its lower end with a stop-cock or globe-valve, Y', and 95 to the upper end of the said pipe Y is attached a safety escape-valve, Y².

Z represents a pipe which extends from the upper end of the pipe W and communicates

with the pipe Y between the pipe X and the safety-valve Y^2 , and in the said pipe Z, between the pipes W and Y, is located a stop-cock, Z'.

5 a represents a pipe which extends from the pipe Y to the upper end of a tank or reservoir, b, which contains gasoline. The pipe a is provided with a check-valve, c. The pipe P, which extends upwardly from the pipe O, 10 is connected to the lower side of the gasoline-tank.

The outer end of the pipe Z is provided with a nozzle, d, and the said pipe is also provided with a stop-cock or globe-valve, e. To the 15 outer end of the pipe V is attached a T-coupling, f, which surrounds the nozzle d and from which depends a vertical pipe, h, the lower end of which is open. Near the lower end of the pipe h is a stop-cock, i, and above the said 20 stop-cock in the pipe h is an upwardly-opening check-valve, k.

l represents a pipe which extends from the outer end of the T-coupling f and communicates with a gasometer, m, from which extends 25 the delivery-pipe n.

Below each retort is located a gas-stove, o, the said gas-stoves being connected with a supply-pipe, p, which extends from the gasometer. The said pipe is provided with valves 30 or stop-cocks r, by which communication may be cut off between the said pipes and either or both of the gas-stoves.

The operation of my invention and my method of making illuminating-gas are as follows: Supposing that the gasometer is charged 35 with stored gas at a suitable pressure, the first step in the operation of the machine is to light the burners of the stoves o and cause the heat from the same to thoroughly heat the jackets 40 of the retorts. This requires about fifteen minutes' time. The valves R in the pipe P are then opened, causing a quantity of gasoline to flow from the gasoline-tank through the pipes O and P and through the pipes N into the vertical pipes 45 M, in which it rises until it reaches the pipe L, and from thence passes downwardly through the pipes F into the baskets G. As the said baskets have been heated by hot air in the jackets B, the gasoline is vaporized when it 50 comes in contact with the said baskets, and the vapor escapes through the openings g into the jackets of the retorts, in which it is superheated. The gasoline-vapor then passes upwardly through the pipes E and the pipes I 55 and H into the pipe V, in which pipe it exerts a pressure both ways. The stop-cock e is kept closed until the gage W ^{2} indicates a pressure of forty or fifty pounds. A portion of the vapor finds its way through the pipe a 60 into the top of the gasoline-tank and exerts a sufficient pressure on the gasoline therein to cause a continuous flow of gasoline to be maintained through the pipes into the retorts, as previously described. When the vapor in 65 the retorts is at a suitable pressure, the stop-cock e is opened, and the stop-cock i in the pipes h is also opened to a suitable extent. As

the vapor escapes from the pipe V through the nozzle d, it creates a partial vacuum in the pipe h, thereby sucking a quantity of atmospheric air upwardly through the pipe h, and this air becomes mixed with the gasoline-vapor in the pipe l and forms an illuminating-gas of great purity, uniform pressure, and great candle-power. The gas is discharged from the pipe l into the gasometer or exhauster m, from whence it is carried by the pipe n to the service-pipes and used. By means of the stop-cock i any quantity of air desired may be mixed with the gasoline-vapor, and thus any 80 quality of gas that may be desired can be obtained.

In the event that the flow of gasoline from the tank should be interrupted for any reason, the check-valves S in the pipe O will be instantly closed by the back-pressure of the vapor, and thus prevent the said back-pressure from passing through the pipe P into the bottom of the gasoline-tank. The function of the valves Y^2 is to prevent an undue pressure of 90 gas from being maintained in the retorts, and thus avoid the possibility of an explosion. The pipe Y' is an escape-pipe to be used when making repairs while the pressure of gas is maintained in the machine. 95

When a very fine quality of gasoline is used, I close the right-hand stop-cock, K, and open the stop-cock U in the pipe P. This causes the gasoline to be first fed to the left-hand retort, in the manner hereinbefore described, and there vaporized, and from thence forced through the pipe T into the right-hand retort and there superheated before being fed to the pipe V. This causes all of the gasoline to be vaporized into gas, and entirely prevents 105 waste or loss of the gasoline. I am thus enabled to make an illuminating-gas out of any quality of gasoline, and the gas manufactured by this machine is of an even quality, very 110 pure, of an even temperature, and is not more liable to freeze or condense than is the best of coal-gas.

Another advantage gained by a machine thus constructed is that there is no residue left in the machine, as all the gasoline is utilized in making the gas. The stoves o, which consume gas generated by this machine, burn without soot or smoke, and thus there is no necessity for providing chimneys or pipes which convey away the products of combustion. 115

In a small gas-machine which I have constructed and used for the past six months I have made five thousand cubic feet of twenty-eight-candle power gas per hour with ease, 120 and at a cost of about sixty cents per thousand feet, which is very much less than the cost of the best coal-gas.

A gas-machine thus constructed is cheap and simple, can be run very economically, 125 will manufacture a superior quality of gas at a very low cost, and is not likely to explode.

I am aware that it has been heretofore proposed to utilize coal-tar as fuel by forcing the

same, in the form of spray, into a combustion-chamber in which active combustion is maintained; but such is not my invention, and this I disclaim.

5 I am also aware that it has been heretofore proposed to make a fixed illuminating-gas by combining the vapor from coal-tar, or distilled coal, or from heavy oils, with vapor from petroleum naphtha, mixing the said vapors with superheated steam or heated air, and then forcing the mixture through a red-hot retort, and this, also, I disclaim.

Having thus described my invention, I claim—

15 1. In apparatus for manufacturing gas, the combination of the retort, the pipe E, leading therefrom, the perforated basket in the retort, and the pipe F, communicating with the basket to introduce gasoline thereto, substantially as described.

25 2. In apparatus for manufacturing gas, the combination of the retort, the vertical outlet-pipe E, extending into the retort and communicating with the lower end thereof, the inlet-pipe F, surrounding the upper portion of the pipe E, and the perforated basket attached to the lower end of the pipe F, communicating therewith and located in the retort, substantially as described.

30 3. In apparatus for manufacturing gas, the combination, with the retort, of the inlet-pipe having the communicating depending pipe M, closed at both ends, and the pipe N, extending to the bottom of the pipe M and communicating therewith, substantially as described.

35 4. In an apparatus for manufacturing gas, the combination of the generating-chambers and means for heating the same, the gasoline-tank, pipes respectively from the upper and lower portions of the tank to the generating-chambers, and provided with check-valves, as described, and a pipe, E, basket, and pipe F, leading from the same, substantially as described.

45 5. In an apparatus for making gas, the combination of the generating-retorts and means for heating the same, of a supply-tank communicating at its upper and lower portions

with said generating-chambers, a vapor-pipe, V, leading from said chambers, and an air-pipe communicating with the vapor-pipe, substantially as set forth. 50

6. In an apparatus for making gas, the combination of the generating-chambers and means for heating the same, spraying-basket located therein, a supply-tank communicating with said basket, and a pipe communicating with the upper portion of the tank and leading to the generating-chambers, and a pipe, V, leading from said chambers and terminating in a nozzle, a chamber surrounding said nozzle, and a pipe intersecting the same, substantially as set forth. 55

7. In an apparatus for making gas, the combination of the generating-chambers and means for heating the same, a vaporizing-basket located therein, a supply-tank communicating with said basket, the vapor-pipe, V, leading from said chambers, the mixing-chamber f, the air-pipe communicating with said chamber, the pipe l, leading therefrom, and the gasometer or exhauster communicating with the pipe l, substantially as set forth. 65

8. In an apparatus for manufacturing gas, the combination of the generating-chambers, basket therein, inlet and outlet pipes therefor, the pipe H, connecting the inlet-pipes of the chambers and having stop-cocks K, and the pipe T, leading from the inlet-pipe of one chamber and to the pipe H and having the cock U, substantially as set forth. 75

9. In apparatus for manufacturing gas, the combination of the retorts having the inlet-pipes and the outlet-pipes, the pipe H, connecting the inlet-pipes of the retorts and having the stop-cocks K, and the pipe T, leading from the inlet-pipe of one retort to the pipe H and having the stop-cock U, substantially as described. 85

In testimony that I claim the foregoing as my own I have hereto affixed my signature in presence of two witnesses.

APIAUS CLAUDIUS SWAIN.
